UNITED STATES PATENT OFFICE.

HENRY P. CLAUSEN, OF CHICAGO, ILLINOIS, ASSIGNOR TO AMERICAN ELECTRIC TELEPHONE COMPANY, A CORPORATION OF NEW JERSEY.

TELEPHONE SYSTEM.

SPECIFICATION forming part of Letters Patent No. 701,152, dated May 27, 1902.

Application filed April 26, 1901. Serial No. 57,530. (No model.)

To all whom it may concern:

Be it known that I, HENRY P. CLAUSEN, a citizen of the United States of America, and a resident of Chicago, Cook county, Illinois, have invented a certain new and useful Improvement in Telephone Systems, of which the following is a specification.

My invention relates to improvements in telephone systems, and more especially to those systems having a central office at which subscribers' lines terminate, with means at such office to manually connect the lines together for conversational purposes, together with apparatus for completely supervising connections and performing all other necessary operations.

The object of my invention is the simplification of systems of the class described, to reduce the labor of the operators at the central office in making and taking down connections, to furnish a complete supervisory system of signals for established connections, as well as a means of automatic signaling from the substations to the central office, and, in general, to provide an efficient and economical system throughout.

To the accomplishment of these and such other objects as may hereinafter appear, the invention consists in a system in which the subscribers' stations are provided with the usual apparatus and in which the calling of the central office and the clearing-out signal are accomplished by merely taking up and replacing the receiver. A grounded signaling-bell is also provided at the stations, which may be a low-wound bell, if preferred, and therefore cheap. The central office equipment comprises cord-circuits having the tips and sleeves of the plugs connected by the cord-strands. Relays are bridged across the strands with the middle point of the bridge connected with the common battery, which also operates the line-signals. Each such relay is subservient to the operation of the corresponding subscriber's hook-switch, and when operated gives a distinctive signal and further operates means to open the circuit to the other station to prevent the undesired operation of the other relay. Means are also provided to enable the operators to talk with the subscribers at all times.

The invention further consists in the novel arrangement and constructions hereinafter described, and particularly pointed out in the claims, reference being had to the accompanying drawings, forming a part hereof, in which the same reference characters indicate like parts throughout the several views, and in which—

Figure 1 is a diagram of two subscribers' stations in lines and the central office apparatus. Fig. 2 is a diagram in simplest form of two connected substations. Fig. 3 is a diagram of a modification of the central office apparatus.

In the figures, A and B designate subscribers' stations where the usual apparatus is employed, including the transmitters 2, local batteries 3, induction-coils 4, receivers 5, and telephone hook-switches 6, connected to one of the pair of line conductors and a signal-bell 7 in a grounded branch from the normal or resting contact of the hook. The metallic lines comprising the conductors 8 and 9 extend to the central office, where they connect with spring-jacks 10, having springs 11 and 12, which are normally connected with the grounded branch 11', including the individual line-signal 13 and the lead 30 of the common battery 14, that is grounded, as shown at G.

The operator's connective means at the central station includes the cord-circuit, having the answering and connecting plugs p and p' at each end thereof, the cord-strands 17 and 18 each extending from the tip-contact 19 of one plug to the sleeve-contact 20 of the other. The usual listening and ringing key is provided and is indicated conventionally in the drawings, the spring 21 being adapted to connect the operator's telephone with the cord-circuit and the springs 22 to similarly connect the grounded ringing generator 15 with the plug p'. The supervisory signals 23 and 24, which are preferably lamps, are associated with the respective ends or plugs of the cord-circuit and serve when a connection is established to indicate the condition of the telephone at the subscribers' stations of the connected lines—that is, if the receivers are or are not upon their hooks. These signals are operated or controlled by relays 25 and 26,

- located in a bridge or connection 16 across the cord-circuit, a point of which intermediate the said relays is connected with the battery 14 by the branch conductor 14'. 5 These relays of course may be replaced by relays of other suitable form or character, each coil having an armature or other equivalent construction and arrangement. The supervisory lamp-circuits are extended 10 through the front contacts and armatures of the relays 25 and 26 by conductors 23' and 24' to a common conductor 27, that includes the relays 28 and 29 and connects with the common battery-lead 30, the latter relays 15 serving by their armatures and back contacts to open the cord-strands 17 and 18 at the points indicated.
- In the operation of the system the subscriber A removes his receiver from the hook, 20 thus closing a circuit from ground G at central through the common battery 14, lead 30, line conductor 9, receiver 5, secondary of the induction-coil 4, through the hook, line-wire 8, conductor 11', and line-signal 13 to ground 25 and operating his individual signal 13. The operator upon seeing the signal exposed inserts the plug *p* in the jack 10 of the subscriber calling and connects her telephone therewith by means of the springs 21 of the 30 listening and ringing key. Upon learning the number of the wanted party she inserts the calling-plug *p'* into the jack 10 of that subscriber and connects the ringing generator with that end of the plug-circuit by means 35 of springs 22 of the ringing and listening key, which rings the subscriber's bell over the grounded line conductor 8 and the tip-strand 18 of that end of the cord-circuit. When the answering-plug *p* was first inserted in the 40 jack 10, the corresponding relay 25 did not operate for the reason that the ground branch at the subscriber's station was removed and no complete circuit for the same was established with the hook; but as soon as 45 the plug *p'* was inserted a path for current from the battery 14 was provided through the conductors 14' and 16, relay 26, cord-strand 18 to the tip-contact of the plug *p'* to line-spring 11 of jack 10 and over line conductor 8 to station B, and thence through the telephone hook-switch 6 and bell 7 to ground. This suffices to operate the relay 50 26, lighting the lamp 24 associated with that end of the cord-circuit or plug *p'*, over a circuit from the battery 14 through the common conductor or lead 30 to conductor 27 on either side of the battery through branch conductor 24', armature, and front contact of relay 26 to supervisory lamp 24 and ground. 55
- 60 This signal indicates to the operator that the subscriber has not yet responded to the call. This lamp-circuit also includes in its parallel paths formed by conductor 27 the relays 28 and 29, which are at this time energized to attract their armatures and open the cord-strands 17 and 18 at the points shown, the said strands including the armatures and

resting-contacts of said relays in the end portions over which the relays 25 and 26 are not operated. The function for so opening the 70 cord-strands on the other side of the bridge 16 from that over which the said relays are operated is to prevent the operation of the other relay—in this case relay 25—over the cord-strand 17, line conductor 8, to the station A and back over conductor 9, strand 18, to ground at station B, for this would have the effect of lighting supervisory signal 23 to the confusion of the operator; but the opening of the cord-circuit by means of the relay 80 28 prevents this undesired operation of the relay 25 over the metallic circuit and at the same time leaves intact the strand 17 from the bridge 16 to the plug *p*, over which, together with line-wire 8, the relay 25 may be 85 operated by current from battery 14 when the subscriber's receiver is upon the hook. This arrangement of circuits and action is illustrated more simply in Fig. 2, where the station A is shown with the hook-switch up 90 and the station B with the hook-switch down. Under these conditions the path for current from the battery 14 will be from ground at the central station through the relay-coil 26 over the line-wire 8 to ground at station B. 95 This will operate the corresponding supervisory signal; but if the circuit be not opened through to the other line A by the relay 28 a parallel path for current from the battery 14 will exist through the other relay 25, line-wire 100 8, to the station A, and back to the central office over the line-wire 9, where it joins the current already upon the conductor 8 and passes to ground at the station B. This would operate the relay 25 and, as explained, this 105 is undesirable. To prevent this, the relays 28 and 29 are provided, which serve, whenever one of the bridged relays is energized, to open the metallic circuit to the other line and at the same time leave intact a circuit 110 over which such line-signal can be controlled. When the wanted subscriber responds to the signal, the ground is cut off thereat and the relay 26 is deenergized to extinguish the lamp 24. At the termination of the conversation 115 both receivers are returned to their hooks and both lamps are lighted, whereupon the operator withdraws the plugs and all parts are restored to normal position.

While in Fig. 1 I have shown relays 28 and 29 joined by the common wire 27 and both operated whenever either relay 25 or 26 is energized, it is not necessary to the successful operation of my invention that both said relays be operated at the same time, since it is 125 only necessary to operate the relay associated with one end of the circuit when only the supervisory lamp associated with the other end of the circuit is operated. An arrangement of circuits whereby this is accomplished is 130 shown in Fig. 3, (the corresponding parts being designated as before,) wherein the relays 28 and 29 are shown in separate branches 27^a and 27^b with their corresponding lamps 23 and

24, the continuity of the circuits of which are controlled by the relays 25 and 26, the latter being interchanged in the diagram. When in this arrangement the relay 26 is operated by 5 the substation B, the corresponding lamp 24 is lighted and the relay 28 is operated to open the other end of the cord-circuit. A similar operation takes place with reference to the relay 25 and station A. For convenience and 10 simplification, however, I prefer the arrangement shown in Fig. 1, as it is not objectionable to operate both relays 28 and 29 simultaneously.

In order to provide means for the operator 15 to communicate with either station A or B whenever the relay 28 or 29 is energized, I bridge the break produced thereby by means of condensers 40, as shown in Fig. 1, which allows the operator to converse with either 20 station, even though the strand thereto is opened by the relay-armatures. If preferred, high resistances 41, as shown in Fig. 2, may be used in place of the condensers; but they should be comparatively high—about five 25 thousand ohms—in order to not defeat the very object of opening the circuit by the relays.

It will be observed that this system embodies all the advantages of a common battery system, so far as signaling the central office 30 from the subscribers' stations and complete supervision of all connections are concerned, and in addition those of a through talking-circuit without the inconvenience usually incident to arrangements of this character. In 35 addition low-wound bells may be used for the substations and other advantages gained. Others suitable generators may be used in place of the storage batteries 14. A common return-conductor may replace the ground connection. The proper dimensions of the electrical parts are obvious to those skilled in the art to which the invention appertains, and are accordingly not herein stated.

For the above-described operation it will 45 be observed that the hook-switches must be connected with the line-wires in the same unvarying relation, the wires to the jacks with similar precision, and the strands of the cord-circuits should extend between tip and sleeve 50 contacts of the plugs. Other relations may exist and still be operative, and I do not wish to be considered as holding that the improvement in all its features and aspects is limited to that shown and described.

55 While I have described the invention with reference to the various details of construction and arrangement, I do not wish to be limited thereto, as various changes, alterations, and modifications may be made therein 60 without departing from the scope or principle thereof; but,

Having thus particularly described my invention, what I claim, and desire to secure by Letters Patent, is—

65 1. In a telephone system, the combination with subscribers' lines, of a central office at which the lines terminate, operators' connect-

ive means at the central office to variously connect said lines together for conversational purposes, supervisory signals associated with 70 said means to indicate the condition of the telephones at the connected subscribers' stations, and a circuit-breaking device adapted to open the circuit to one station when the supervisory signal assigned to the other is 75 operated.

2. In a telephone system, the combination with subscribers' lines, of a central office at which the lines terminate, operators' connective means at the central office to variously connect said lines together for conversational purposes, subscribers' stations having telephones and hooks, and circuit-breaking device adapted to open the circuit to one of two connected subscribers when the telephone of 85 one subscriber is off the hook and the telephone of the other subscriber is upon the hook.

3. In a telephone system, the combination with subscribers' lines, of a central office at 90 which the lines terminate, operators' connective means at the central office to variously connect said lines together for conversational purposes, subscribers' stations being provided with telephones and hooks, and a relay 95 and circuit connections adapted to open the circuit to a connected subscriber when his telephone is off the hook and the other subscriber's telephone is upon the hook.

4. In a telephone system, the combination 100 with subscribers' stations having receivers and hook-switches, metallic telephone-lines extending therefrom to a central office, operators' connective circuits to connect said lines together for conversational purposes, and a 105 relay adapted and arranged to open one side of the circuit of a connected subscriber when one subscriber's receiver is off the hook and the other subscriber's receiver is upon the hook. 110

5. In a telephone system, the combination with subscribers' stations having receivers and hook-switches, metallic telephone-lines extending therefrom to a central office, operators' connective circuits to connect said lines 115 together in pairs for conversational purposes, supervisory signals associated with said means to indicate the condition of the subscribers' instruments when connected together, and a circuit-breaking device adapted 120 and arranged to open the circuit to one connected subscriber when the supervisory signal assigned to the other is operated.

6. In a telephone system, the combination with subscribers' stations having receivers 125 and hook-switches, metallic telephone-lines extending therefrom to a central office, operators' connective circuits to connect said lines together in pairs for conversational purposes, supervisory signals associated with said 130 means to indicate the condition of the subscribers' instruments when connected together, said signals being operated over one side of the metallic circuits and ground, and

a relay adapted and arranged to open the other side of the circuit to one subscriber when the supervisory signal for the other subscriber is operated.

- 5 7. In a telephone system, the combination with metallic telephone-lines, subscribers' stations having hook-switches connected to one line conductor and normally grounded, cord-circuits at the central office to interconnect said lines for conversational purposes, relays connected across the line, a common battery connected between said coils and ground, supervisory signals controlled by said relays, and relays arranged for automatically 15 opening the metallic circuit of one connected line when the signal of the other is operated.

8. In a telephone system, the combination with metallic telephone-lines, subscribers' stations having hook-switches connected to 20 one line conductor and normally grounded, cord-circuits at the central office to interconnect said lines for conversational purposes, relays connected across the line, a common battery connected between said coils and ground, supervisory signals controlled by said 25 relays, and circuit-breaking devices controlled by said relays for opening the circuit to one station when the signal assigned to the other is operated.

- 30 9. In a telephone system, the combination with metallic telephone-lines, hook-switches at the subscribers' stations connected to one line conductor in the same unvarying relation and normally grounded, cord-circuits to 35 interconnect said lines for conversational purposes having their strands connected with tip and sleeve contacts of the plugs, circuit-closing relays bridged across the cord-circuits, a common battery connected between 40 a point intermediate said relays and earth, supervisory signals controlled by said relays and associated respectively with the ends of the cord-circuit, and circuit-breaking relays also controlled by said circuit-closing relays 45 to open either end of the cord-circuit when the signal associated with the other end is operated.

10. In a telephone system, the combination with metallic lines, hook-switches at the subscribers' stations connected to one line conductor in the same unvarying relation and normally grounded, cord-circuits to interconnect said lines for conversational purposes having their strands connected with tip and 50 sleeve contacts of the plugs, relays bridged across the cord-circuits, a common battery connected between a point intermediate said relays and earth, said relays being operated over the grounded line conductors and corresponding strands of the cord-circuit, supervisory signals associated with the ends of the cord-circuit, and relays for opening the other strands of the cord-circuit, said latter relays being operated when one subscriber's receiver 55 is upon the hook and the other subscriber's receiver is off the hook.

11. In a telephone system, the combination

with metallic lines, hook-switches at the subscribers' stations connected to one line conductor in the same unvarying relation and normally grounded, a cord-circuit to interconnect said lines for conversational purposes, circuit-closing relays connected across the cord-circuit, a common battery connected between a point intermediate said relays 75 and earth, supervisory signals controlled by said relays assigned to each end of the cord-circuit, circuit-breaking relays to open each end of the cord-circuit also controlled by said circuit-closing relays, and local circuits each 80 including said battery and one of said circuit-breaking relays, the circuit-breaking relay at one end of the cord-circuit operating when the supervisory signal at the opposite end is operated.

85 12. In a telephone system, the combination with metallic telephone-lines, hook-switches at the substations connected in unvarying relation with one line conductor, signal-bells grounded by said hook-switches, a central office at which the lines terminate, individual signals at said office for said lines, a common battery to which said lines and signals are normally connected, an operator's cord-circuit comprising plugs and strands between 90 the tip of one plug and sleeve of the other, two circuit-closing relays in a bridge of the cord-circuit, the middle point of which bridge is connected with said battery, said relays being adapted to be operated over the grounded 100 line conductors and corresponding strands of the cord-circuit when a connection is established, supervisory signals associated with said plugs and controlled by said relays, and circuit-breaking relays to open the cord-strand on one side of the bridge when a circuit-closing relay is operated over the other strand on the other side.

105 13. In a telephone system, the combination with metallic telephone-lines, hook-switches at the substations connected in unvarying relation with one line conductor, signal-bells grounded by said hook-switches, a central office at which the lines terminate, individual signals at said office for said lines, a common 110 battery to which said lines and signals are normally connected, an operator's cord-circuit comprising plugs and strands between the tip of one plug and sleeve of the other, two circuit-closing relays in a bridge of the 115 cord-circuit, the middle point of which bridge is connected with said battery, said relays being adapted to be operated over the grounded line conductors and corresponding strands of the cord-circuit when a connection is established, supervisory signals associated with 120 said plugs and controlled by said relays, and circuit-breaking relays arranged to open the cord-strands and operated by either of the circuit-closing relays, whereby when a signal 125 associated with one plug is operated the circuit-breaking relays are also operated to open the cord-strands.

130 14. In a telephone system, the combination

with metallic telephone-lines, hook-switches at the substations connected in unvarying relation with one line conductor, signal-bells grounded by said hook-switches, a central office at which the lines terminate, individual signals at said office for said lines, a common battery to which said lines and signals are normally connected, an operator's cord-circuit comprising plugs and strands between the tip of one plug and sleeve of the other, two circuit-closing relays in a bridge of the cord-circuit, the middle point of which bridge is connected with said battery, said relays being adapted to be operated over the grounded line conductors and corresponding strands of the cord-circuit when a connection is estab-

lished, supervisory signals associated with said plugs and controlled by said relays, circuit-breaking relays arranged to open the cord-strands and operated by either of the circuit-closing relays, whereby when a signal associated with one plug is operated the circuit-breaking relays are also operated to open the cord-strands, and a grounded ringing generator at the central office to operate the subscribers' bells.

Signed by me at Chicago, Cook county, Illinois, this 24th day of April, 1901.

HENRY P. CLAUSEN.
